UNITED STATES PATENT OFFICE

147,107

DESIGN FOR A FOUNTAIN PEN

Charles T. Breitenstein, Chicago, Ill., assignor, by
mesne assignments, to Holly Pen Corporation,
Chicago, Ill., a corporation of Illinois

Application April 6, 1946, Serial No. 128,343

Term of patent 3½ years

(Cl. D74—17)

To all whom it may concern:

Be it known that I, Charles T. Breitenstein, a citizen of the United States and a resident of Chicago, in the county of Cook and State of Illinois, have invented a new, original, and ornamental Design for a Fountain Pen, of which the following is a specification, reference being had to the accompanying drawing, forming a part thereof.

Figure 1 is a side elevational view of a fountain pen showing my new design with the writing end covered.

Figure 2 is a front elevation with the cap in disassembled relation to the body of the pen and rotated 90 degrees from the position illustrated in Fig. 1.

I claim:

The ornamental design for a fountain pen, substantially as shown and described,
CHARLES T. BREITENSTEIN.
